US0D1082990S

(12) **United States Design Patent** (10) **Patent No.:** **US D1,082,990 S**
(45) **Date of Patent:** **** Jul. 8, 2025**

(54) **GLOVE RETENTION DEVICE**

(71) Applicant: **Implus Footcare, LLC**, Durham, NC (US)

(72) Inventors: **Giovanni Erick Guidetti, III**, Rancho Santa Margarita, CA (US); **Daniel Case Fuchs**, Encinitas, CA (US)

(73) Assignee: **IMPLUS FOOTCARE LLC**, Durham, NC (US)

(**) Term: **15 Years**

(21) Appl. No.: **29/826,993**

(22) Filed: **Feb. 16, 2022**

(51) **LOC (15) Cl.** **21-02**

(52) **U.S. Cl.** USPC **D21/780**

(57) **CLAIM**

The ornamental design for a glove retention device, as shown and described.

DESCRIPTION

FIG. 1 is a top perspective view of a glove retention device; FIG. 2 is a left side view of the glove retention device of FIG. 1;

FIG. 3 is a right side view of the glove retention device of FIG. 1;

FIG. 4 is a front view of the glove retention device of FIG. 1;

FIG. 5 is a rear view of the glove retention device of FIG. 1;

FIG. 6 is a top view of the glove retention device of FIG. 1; and,

FIG. 7 is a bottom view of the glove retention device of FIG. 1.

1 Claim, 5 Drawing Sheets
